UNITED STATES PATENT OFFICE.

CARL BERANEK, OF JAROSLAU, AUSTRIA-HUNGARY.

TIGHTENING DEVICE FOR HARNESS.

SPECIFICATION forming part of Letters Patent No. 722,077, dated March 3, 1903.

Application filed December 30, 1901. Serial No. 37,816. (No model.)

To all whom it may concern:

Be it known that I, CARL BERANEK, a subject of the Emperor of Austria-Hungary, residing at Jaroslau, in the Province of Galicia, 5 in the Empire of Austria-Hungary, have invented certain new and useful Improvements in Tightening Devices for Saddles; and I do hereby declare the following to be a full, clear, and exact description of the invention, 10 such as will enable others skilled in the art to which it appertains to make and use the same, reference being had to the accompanying drawings, and to letters of reference marked thereon, which form a part of this 15 specification.

This invention relates to riding-saddles, and has for its object to provide an improved device for tightening and loosening the saddle-girths of riding-saddles and to reduce to a 20 minimum the power and time ordinarily required for adjusting the same. The free end of the saddle-girth is fixed to a clasp provided with two laterally-disposed pins or studs adapted to engage in two angle-iron racks 25 secured to the saddle, the arrangement being such as to cause the said clasp to form a tightening-lever which when in its upright position tightens the saddle-girth and releases said girth when turned downward. 30 By placing the studs of the lever in higher or lower teeth of the side racks it will be easy to lengthen or shorten the effective length of the girth, as may be required.

Figures 1 and 2 of the accompanying drawings represent a saddle provided with the 35 tightening device, the girth being shown in its loosened and tightened position, respectively. Fig. 3 is the front view; Fig. 4, the side view of the tightening-clasp. Fig. 5 represents an angle-iron rack in side elevation.

According to this invention to the saddle-flap *a* are affixed two angle-iron racks formed with a number of superposed notches. The end of the saddle-girth *d* is provided with a 45 clasp or tightening-lever *e*, having at its lower end two exchangeable pivot pins or studs *f*, adapted to engage in the notches *c* of the angle-iron racks *b*, above described. The clasp *e* is curved to correspond to the form of the 50 saddle-flaps, Fig. 4, so that when said lever is in its upright position the pull of the girth

will tend to keep it closely pressed to the side of the saddle. This lever is advantageously provided with a handle *g* to facilitate the manipulation of the same. The other end of 55 the saddle-girth is attached to the opposite flap of the saddle and may, if desired, be furnished with a buckle device for adjusting its effective length.

For adjusting the saddle upon the animal 60 the clasp with its handle downward is by means of its pins introduced in the lower notches *c* of the angle-iron racks. The saddle-girth is then roughly adjusted from the right-hand side of the saddle by means of the 65 buckle. Upon raising the handle of the clasp the saddle-girth will be effectively tightened. If during a long ride the girth has slackened and it is found necessary to tighten it again, this may readily be effected in the saddle 70 without dismounting by turning down the clasp *e* and placing its pins or studs in the next higher notches *c* of the racks and then again raising the clasp.

The clasp when in its raised position will 75 constantly remain in its tightened position owing to the fact that the pull of the girth is directed rearward of the pins or studs.

In order to prevent the tightening device being rendered useless by the unexpected 80 breaking of one of the pins or studs *f*, which are made exchangeable, the clasp is provided with other projecting pins *h* at a suitable distance above the pins or studs *f*, first described, and arranged to enter the notches *c* in the 85 racks without, however, taking a bearing therein. Thus if one of the first set of pins *f* should accidentally break the lever will slightly descend at that side till the pin *h* above is firmly seated in its notch, and it is therefore 90 not necessary for the rider to dismount at once to attend to the exchange of the broken stud by a new one, but he can postpone this exchange for a subsequent more suitable occasion.

I claim—

1. The combination with a saddle and two parallel bars secured vertically to one of its flaps and having a plurality of notch-bearings in their outer face, the space between the bars 100 somewhat greater than the width of a saddle-girth; of a lever provided with fulcrum-studs

adapted to be placed in the aforesaid bearings, and a saddle-girth secured to the outer face of said lever intermediate its ends, for the purpose set forth.

- 5 2. The combination with a saddle and two parallel bars secured vertically to one of its flaps and having a plurality of notch-bearings in their outer face, the space between the bars somewhat greater than the width of a saddle-girth; of a lever comprising a body portion consisting of a substantially rectangular plate provided on its upper edge with a handle extension and with fulcrum-studs at its opposite lower corners, adapted to be placed in the aforesaid bearings, and a saddle-girth secured to the outer face of said body portion intermediate its upper and lower edges, for the purpose set forth.
- 10 3. The combination with a saddle and two parallel arcuate bars secured vertically to one of its flaps and provided with a plurality of notch-bearings in their outer face, the space between the bars somewhat greater than the width of a saddle-girth; of a lever comprising
- 15 25 a body portion consisting of a substantially rectangular plate arc-shaped in longitudinal section and of a width substantially equal to that of the saddle-girth, said body portion provided with a fulcrum-stud at its opposite lower corners adapted to be placed in the aforesaid notch-bearings, and a saddle-girth secured to the outer face of the body portion
- 20 30

of the lever intermediate its upper and lower edges, for the purpose set forth.

4. The combination with a saddle and two parallel vertical bars secured to one of its flaps and provided with notch-bearings in their outer face; of a lever having fulcrum-studs fitting said bearings, and a girth secured to the lever intermediate its fulcrum-studs and opposite end, and means locking the lever to the aforesaid bars should one or both fulcrum-studs break, for the purpose set forth.

5. The combination with a saddle and two parallel bars secured vertically to one of its flaps and having a plurality of notch-bearings in their outer face; of a lever provided with primary fulcrum-studs fitting the aforesaid bearings, and with safety fulcrum-studs at a distance from said primary fulcrum-studs slightly greater than that between two adjacent bearings, and a saddle-girth secured to the outer face of the lever intermediate its fulcrum and opposite end, for the purpose set forth.

In testimony that I claim the foregoing as my invention I have signed my name in presence of two subscribing witnesses.

CARL BERANEK.
